UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING AND LOADING MACHINE.

1,378,360.

Specification of Letters Patent. Patented May 17, 1921.

Application filed August 1, 1913, Serial No. 782,522. Renewed July 17, 1920. Serial No. 397,155.

To all whom it may concern:

Be it known that I, NILS D. LEVIN, a citizen of the United States, residing at Columbus, in the county of Franklin and State of Ohio, have invented certain new and useful Improvements in Mining and Loading Machines, of which the following is a specification, reference being had therein to the accompanying drawings.

10 This invention relates to improvement in mining machines of the type adapted for under-cutting coal, breaking it down and loading it into cars.

I am aware that machines intended to 15 perform these functions have been heretofore proposed and constructed and I do not therefore broadly claim as a part of my present invention breaking down and loading means in combination with an under-

20 cutting means. I am also aware that it has been heretofore proposed to provide in a cutting and loading machine simultaneously movable horizontal under-cutting devices and parallel vertical shearing devices; to

25 provide reciprocating breaking down tools mounted upon a frame work which can be oscillated about a horizontal axis; to provide a car loading conveyer which is pivoted to the main frame for movement about a

30 vertical axis; and to provide ropes or cables together with winding drums for moving the machine as a whole. None of the foregoing features is broadly claimed as a part of this invention.

35 However, by my present invention I have provided a number of features which are new in machines of this character, and the objects of the invention therefore are to provide the following improved features

40 among others: improved rope controlled mechanism for moving the cutter device bodily with respect to the bed frame; improved shear cutting mechanisms adapted to cut kerfs having vertical forward edges; im-

45 proved breaking down devices and improved actuating and controlling mechanism therefor; means supplemental to the main conveyer for gathering and loading the slack from the under-cutting means;

50 means independent of the main power devices for driving the rear swinging conveyer; improved rope controlled means for moving the machine as a whole from one position to another; improved power transmit-

ting devices for driving the various operating parts; improved devices whereby the various parts of the machine may be readily controlled by the operators; and various other features of novelty and advantage which will be readily understood from the following description, and from the drawings.

In the accompanying drawings I have shown one embodiment of my invention. However, I desire it to be understood that 65 various modifications as to details may be made within the scope of the appended claims without departing from the spirit of my invention.

Of the drawings—

70 Figure 1 is a plan view of a machine embodying my invention;

20 Fig. 24 is a fragmentary sectional view along the line 24—24 of Fig. 6;

Fig. 25 is a diagrammatic plan view showing the feeding mechanism, the other parts being removed for the sake of clearness;

Fig. 26 is a detail view of the clamp for holding the pull-back rope;

25 Fig. 27 is a vertical sectional view through the clamp shown in Fig. 26;

Fig. 28 is a fragmentary sectional view taken along the line 28—28 of Fig. 4;

30 Fig. 29 is a fragmentary side view partly in section, and partly in elevation of the parts shown in Fig. 28;

Fig. 30 is a detail view of a part of the feed mechanism;

35 Fig. 31 is a diagram of electrical connections;

Figs. 32—36 are diagrammatic views illustrating the manner of using the machine.

40 Stated very briefly the machine comprises five principal operative parts. These are the under-cutting mechanism indicated in Figs. 1 and 2 by A; the vertical shearing devices B—B; the breaking down mechanism C; the primary conveyer D, and the secondary loading conveyer E.

45 The several principal parts are coöperatively connected together and are mounted upon a main frame 1, which is shown in detail in Figs. 11 and 12. This main frame is supported upon a pan or shoe which rests 50 directly upon the floor of the mine room or entry in which the machine is being operated. The frame is bodily movable with respect to the pan in a manner to be described.

55 Supported on the main frame casting 1 is a relatively movable cutter frame 2 preferably formed of cast steel. The cutter frame is shown in detail in Figs. 13 and 14, and it will be noted that it is generally triangular in outline. As shown in Fig. 7, the cutter frame 2 is provided with horizontal flanges 3 which are slidable in suitable guides 3^a formed on the under side of the main horizontal wall of the frame 60 casting 1. The cutter frame 2 is provided

around its edges with a groove adapted to receive and guide an endless chain 8 to which are secured cutting bits 9—9. The chain groove along the sides of the frame is formed in part by the plates 7—7, and 70 at the front by the plates 7^a—7^a. At the front the chain 8 passes over a hardened wear plate 7^b. At the rear the chain passes around and is engaged by the drive sprocket wheel 10 which is mounted on the main 75 frame to receive power in a manner to be hereinafter described.

As before stated the cutter frame 2 is 80 slide longitudinally with respect to the main frame 1. This adjustment of the cutter frame is for the purpose of regulating the tension in the cutter chain. The adjusting mechanism is clearly shown in Figs. 7 and 17. In the cutter frame 2 there is formed a recess in which is rigidly mounted 85 a screw 4. A bracket 4^a, which is secured to the frame 1, has depending arms with apertures through which the screw 4 loosely passes. 4^b is a combined nut and worm wheel mounted on the screw 4 between the 90 depending arms of bracket 4^a, and this worm wheel is engaged by a worm 4^c on a shaft 4^d, which is mounted in the bracket 4^a. The end of the shaft 4^d is squared to receive a cranked socket wrench 4^e. By means of 95 the socket wrench 4^e an operator at the side of the machine can move the parts which have been described, and can by means of them move the cutter frame 2 longitudinally with respect to the main frame 1, thereby 100 tightening or loosening the cutter chain 8.

Positioned at opposite sides of the main frame 1 and longitudinally slideable thereon are brackets 13—13 to which are secured 105 vertical cutter frame plates 14—14. These parts are clearly shown in Figs. 3 and 7. Each of the brackets 13 has at its outer edge a flange 15 engaging a rib 16 on the main frame, and at its inner edge a flange 17 engaging a rib 18 on the main frame. At 17^a there is on each bracket a downward extending rib which engages a vertical wall on the main frame. It will be clear that by means of the flanges or ribs 15, 17 and 17^a the brackets 13—13, and consequently 110 the plates 14—14, are held against lateral or vertical movement, at the same time being free for longitudinal movement within certain limits. As shown in Fig. 3 the plates 14—14 are substantially triangular 115 in outline. Each plate has a substantially vertical forward edge and is provided at each of its forward corners with an idler sprocket wheel 23 which is journaled on a ball-bearing 24 secured to the frame plate by means of two small plates 24^a. Arranged 120 to pass around the respective plates 14—14 are endless cutter chains 25—25. Each chain 25 is made up of two different kinds of links 26—26 and 27—27. The links 125 130

26—26 are provided with apertures adapted to receive the shanks of cutting bits 28—28, which are held in place by means of wedges 28^a—28^a. As shown in Fig. 7 the bits 5 28—28 are of different kinds some of them having wide cutting edges and others being pointed. Each of the links 27—27 is made up of two flat plates which extend inward at their inner edges to embrace the 10 frame plate 14, and thus serve to guide the chain. As before stated the chains 25—25 pass around the respective plates 14—14 and engage the respective sprocket wheels 23—23. At the rear the chains 14—14 pass 15 over sprocket wheels 29—29, which are mounted on the main frame to receive power in a manner to be hereinafter described. For supporting the chains 25—25 at the 20 lower sides of the frames 14—14 I provide guide plates 29^a—29^a as shown in Figs. 3 and 18. These plates serve to prevent the chains from sagging and can be as long as desired.

On releasing the bolts 20, the frames 25 14—14 can be moved longitudinally with respect to the main frame 1 by means of screws 13^a, of which one is shown in Figs. 3 and 18. It will be observed that the screw 13^a is mounted in a bracket 13^b secured to 30 the bracket 13, and is arranged to engage with the end of the main frame 1. By turning the screws 13^a the brackets 13—13 and the plates 14—14 can be moved forward to tension the chains 25—25. The 35 brackets 13—13 can be locked in adjusted position by means of the bolts 20—20, which extend through the brackets and through slots 20^a—20^a in the main frame casting.

Attached to the edges of the cutter frame 40 2 are protecting plates 11 which extend above the path of the cutters 9—9, and contact with the plates of the shearing cutter heads. These plates 11 are clearly shown in Fig. 18. They serve to prevent pieces of 45 coal from becoming jammed between the cutters or bits of the two chains, thus damaging the machine.

It will be observed that in the drawings I have shown the forward ends or heads of 50 the under cutter and shearing cutter as terminating in different transverse vertical planes. I desire it to be understood, however, that as to this there may be variations. Under most conditions it is found 55 preferable to extend the under-cutting mechanism six inches or more beyond the shearing mechanism. The reasons for this will be made more fully apparent hereinafter. It will also be observed that the under-cutting 60 mechanism is arranged to form a relatively wide kerf, this being necessary for the admission of the conveyer to be hereinafter referred to. The shear cutting mechanisms are arranged to cut as narrow kerfs as possible.

The mechanism for breaking down the coal above the under-cutting mechanism and between the shearing mechanisms is, as before stated, indicated as a whole by C. It comprises a main vertically oscillatory 70 framework which is made up of two tubular legs 30 and 31 which are arranged longitudinally at the sides of the machine, and are connected together at their forward ends by means of a cross member 32. As 75 shown in Figs. 4 and 9 the legs 30 and 31 are provided at their rear ends with trunnions 33—33 which are journaled in bearings 34—34 on the upward extending parts 35—35 of the main frame 1. 80

Bolted to one of the said legs, as for instance 30, is a downward projecting arm 36 which has at its lower end a rope sheave 37. Bolted to the part 40 of the main frame 1 adjacent the arm 36 is a bracket 40^a having 85 at its upper end a rope sheave 41. A rope 38 passes over the sheaves 41 and 37, and has its end secured at 39 to the bracket 40^a. From the sheave 41 the rope passes downward under the sheave 42 secured to the 90 main frame at 42^a, and to a winding drum 43. It will be clear that when the drum 43 is turned by means of the devices to be described, the rope 38 will be wound or unwound and the framework for the breaking 95 down mechanism will be raised or lowered. Bolted to the other leg 31 of the frame work is a bracket 44 to which is secured the upper end of a coil spring 45. The lower end of this spring is seated in a recess 46 of the 100 main frame. This spring 45 serves to press upward on the oscillatory frame work and to aid in supporting it, thus assisting in the movement of it by means of the rope 38.

Slidably mounted within the hollow legs 105 30 and 31 are tubes 47—47. The tubes 47—47 are joined at their forward ends by means of a cross member 48 having a plurality of sockets in which pick bits 49—49 are secured by means of keys 49^a—49^a. 110 These keys 49^a are shown in Figs. 1 and 20 and extend through apertures 49^b in the cross member 48, and engage suitable notches in the shanks of the bits.

The openings in the forward ends of the 115 tubes 47—47 are closed by means of screw threaded plugs 50 against which abut springs 51 contained within the tubes. The rear ends of the springs 51 abut against pistons 52 secured to piston rods 53. The pistons 52 are slidable in the tubes 47, and the rear ends of the piston rods are secured to cross heads 54, which are slidable in the hollow legs 30 and 31. Springs 55 are interposed between the rear sides of the pistons 120 52, and the rear end walls of the tubes 47. Connected to the cross heads 54 by means of wrist pins 54^a are connecting rods 56 which are pivotally connected at their rear ends at 57 to rocker arms 58. These rocker arms 125 58 130

are connected together at their lower ends by means of a cross member 58^a and are journaled in bearings on the main frame by means of trunnions 59—59. 61 is a connecting rod pivoted at its rear end at 60 to one of the rocker arms 58 preferably that on the near side as shown in Fig. 4. The forward end of the connecting rod 61 is mounted at 62 on a crank pin which will be 10 hereinafter referred to.

Embedded in the cross member 32 of the oscillatory frame is an electro-magnet 65 and secured to the cross member of the reciprocating frame is an armature 66 adapted to be engaged by the magnet. The armature 66 can be adjusted with respect to the cross member 48 by turning the nut 66^a. A spring 66^b serves to normally hold the armature at its outermost position, and at the same time permits yielding in case the parts are moved to bring the armature into contact with the magnet.

32^a—32^a are rubber buffers or cushions positioned in sockets in the cross member 32 and adapted to engage the cross member 48 to take up shock.

When power is transmitted through the connecting rod 61 to oscillate the rocker arms 58 and reciprocate the connecting rods 30 56 and the pistons 52 power will be transmitted by means of the springs 55 and 51 to reciprocate the tubes 47 and the cross member 48 together with the picks mounted thereon. With the parts operating in this 35 way the picks would be given a relatively slow reciprocating motion and would be able to strike but relatively feeble blows upon material with which they might come in contact. In order that the speed of the pick 40 mechanism on its forward stroke may be increased to increase the force of the blows struck by the picks the magnet 65 and armature 66 above referred to are provided. When the reciprocating mechanism reaches 45 its inner extremity of movement the magnet 65 is energized, and in this way the pick mechanism is temporarily held against outward movement. However, the outward movement of the pistons 52 at once takes 50 place, the result being that the springs 51 are compressed. At about the time that maximum compression is reached the magnet 65 releases the armature and the pick mechanism is forced suddenly outward by the 55 springs 51 and strikes a powerful blow against the face of the coal. The springs 55 serve to absorb the energy of the blow in case the picks do not reach the coal, or in case the coal breaks down so easily as not to 60 absorb the entire energy. They also coöperate with the buffers 32^a—32^a to absorb the shock incident to the normal return movement of the pick mechanism.

The electrical connections for controlling 65 the magnet 65 are shown in Fig. 31. The

magnet is connected with the main source of current supply of the machine through the conductors 67 and 69, the conductor 67 being connected through the rheostat 68. The conductor 70 is connected across the 70 supply wires for the magnet, and can be used to short circuit the magnet and thus deënergize it. Connected in the conductor 70 is an automatically acting switch 72 which consists of a strip 73 mounted on a 75 rotating disk, and adapted to contact with fingers 74. It will be clear that when the disk is rotated the circuit through the conductor 70 will be completed and the magnet deënergized. The disk 72 is connected to 80 the operative parts of the machine in a manner to be described, and is timed to deënergize the magnet at the proper intervals. 71—71 are normally closed switches which can be opened by means of the buttons 85 75—75. The switches 71—71 are located at convenient points on the machine so that an operator by opening them can maintain the magnet energized, and thus hold the pick mechanism against operation. If desired, 90 means may be provided for locking the switches 71—71 in open positions.

The main conveyer for the machine is of the endless chain scraper type and extends over substantially the entire width and the 95 entire length of the main frame. The conveyer is shown in Figs. 3, 4, 6 and 7. It comprises two endless chains 75 which are joined at intervals by cross bars 76 which act as scrapers. The chains pass around sprocket 100 wheels 77 on the transverse drive shaft 78 mounted in bearing brackets 79 on the main frame 1. At the front of the machine the chains 75 pass around sprockets 80 on a transverse shaft 81 journaled in bearings 105 82 in the cutter frame 2. The upper strand of the conveyer travels over the surface of the plate 83 which is connected by means of suitable angle bars 83^a—83^a with side plates 84—84. Angle bars 85—85 are secured to the plates 84—84 above the upper strand of the conveyer and serve to protect 110 the chains and hold them in position. The lower strand of the conveyer travels over the surface of a plate 86 which is secured 115 to the plates 84—84 by means of angle bars 87—87. The conveyer trough formed by the vertical plates 84—84 and the horizontal and inclined plates 83 and 86 is a rigid self supporting structure. The trough is 120 mounted at its rear end on the ears 79^a of the bearing brackets 79 for the shaft 78. The forward end is adjustably mounted in the cutter frame 2, the parts being so arranged that the entire forward end of the 125 conveyer can extend into the kerf formed by the cutters 9—9. The position of the forward end of the conveyer with respect to the other parts is shown in Fig. 3, and in Figs. 15 and 16 the mounting for the for- 130

ward end of the conveyer is shown in detail. 82 represents as a whole the bearing for one end of the shaft 81. This bearing is freely slideable in a pocket or depression 82^a formed 5 in the cutter frame 2. The bearing 82 is also adjustable with respect to the main part of the conveyer trough, and adjustment can be effected by means of the screw 82^b. This mounting of the bearings 82 for 10 adjustment both with respect to the trough, and with respect to the cutter frame makes possible the adjustment of the shaft 81 with respect to the conveyer frame to regulate the tension in the conveyer chains, and also 15 makes possible the free movement of the cutter frame to effect tensioning of the cutter chain.

The main conveyer can be readily removed from the other parts of the machine. 20 Ordinarily the roof of a mine is too low to permit the conveyer being lifted off over one side of the machine, and therefore provision is made for drawing it out at the rear end. The conveyer can be entirely freed 25 from the other parts of the machine by disconnecting the bearing brackets 79 from the main frame, and by disconnecting the bearings 82 from the cutter frame. The whole conveyer mechanism can then be drawn directly rearward. Rollers 88 are provided 30 for temporarily supporting the forward parts of the conveyer during such rearward movement.

The rear or swinging conveyer is indicated by E in Figs. 1 and 2. The active element of the conveyer is of the endless chain scraper type, and is similar to the active element of the main conveyer. The two chains of the conveyer are indicated by 35 89—89 and the transverse scraper elements are indicated by 90—90. At the rear the chains 89—89 run over idler sprocket wheels 91 on the transverse shaft 92. At the forward end the chains run over idler sprocket 40 wheels 94 on the transverse shaft 95. The shaft 95 is mounted in suitable bearings in the hopper casting 96. This casting 96 is formed with upward extending flaring walls 45 97 which are positioned and adapted to receive material discharged from the rear end of the main conveyer. Sprocket wheels 98 engage the lower strand of the conveyer chains 89—89 to drive the conveyer. The devices for mounting and driving the 50 sprocket wheels 98 will be hereinafter described.

The trough for the swinging conveyer is made up of two sections which are pivoted together for relative movement about a 55 transverse horizontal axis. The forward section of the trough consists of a plate 99, on which the upper strand of the conveyer rests, and of side walls 100 and 100^a. The lower sections 100 of the side walls are continuations of the flaring hopper walls 97,

and are formed as integral parts of the main hopper casting 96. The rear parts 100^a of the side walls of the forward section of the conveyer trough are secured to the forward parts 100 and to the framework which comprises two pairs of structural steel sections 101 and 102 all of which are bolted or riveted at their forward ends to the main hopper casting 96. Vertical sections 103 connect the sections 101 and 102 near their 70 rear ends. The bottom plate 99 of the trough is connected to the side walls in any usual or preferred manner. As before stated this plate serves to support the forward part of the upper strand of the conveyer. The 80 forward part of the lower strand is supported in part upon the bottom wall of the main hopper casting 96, and in part on the angle bars 104 secured to the frame sections 102. The bars 104 terminate some distance 85 from the sprocket wheels 98 and the conveyer element is permitted to sag at this place in order to allow for adjustment of the parts to be described.

At the rear ends of the structural steel 90 members 102 are bearings for a transverse hinge shaft 105. Upon the ends of this hinge shaft 105 are mounted supporting arms 106, to the rear ends of which the trough for the rear section of the conveyer 95 is secured. This trough extends substantially horizontally and is made up of the side plates 108—108 which flare outward at their upper parts, and the transverse plates 109 and 110 for supporting respectively the 100 upper and lower strands of the conveyer. These plates 109 and 110 are secured to the side plates by means of suitable angle bars and at 110^a—110^a there are provided supplemental flanges for protecting the upper 105 strands of the conveyer chains, and holding them in position. The rear transverse shaft 92 is mounted in suitable bearings secured to the trough and can be adjusted longitudinally by means of the screws 92^a. The forward ends of the supporting arms 106 are pivotally connected to the upper ends of rods 111. The lower ends of the rods are connected to a cross head 112 which is threaded on a vertical screw 113. This 110 screw is mounted in a suitable bearing in a cross member 114 which extends between the frame members 101. A hand wheel 115 is secured to the screw 113 and by turning the hand wheel the cross head 112 can be moved, 115 thus causing the adjustment of the rear section of the conveyer to raise or lower the rear end thereof.

116 is a frame casting rigidly secured to the main frame casting 1. At 117 it is provided with a recess in which, by means of a ball bearing 118, there is mounted a pivot pin 119. The upper end of the pivot pin 119 is adapted to extend into a slot in the hopper casting 96, and a head on the pin serves 120 130

to prevent upward movement of the hopper casting with respect to the frame casting 116. A transverse lock bolt 119^a serves to normally hold the hopper casting 96 against 5 longitudinal movement with respect to the pin. At 120 are rollers secured to the hopper casting 96, and adapted to rest upon a curved rail 120^a which is concentric with the pin 119. It will be clear that the rollers 120 10 coöperate with the pin at 119 to support the entire swinging conveyer, at the same time permitting free oscillatory movement to one side or the other. The entire swinging conveyer can be readily removed by withdrawing 15 the bolt 119^a, thus permitting the whole structure to be moved rearward to disengage the hopper casting 96 from the head of the bolt 119.

Mounted on the rear part of the structural 20 frame work of the swinging conveyer is an electric motor 121 receiving its current through the flexible conductor 122. Conveniently located on the conveyer frame at 123 is a snap switch for controlling the motor 121. The armature pinion 124 of the motor meshes with a spur gear 125 on a suitably mounted shaft 126. On the shaft 126 is a worm 127, which meshes with a worm wheel 128 on a transverse shaft 129 25 which also carries the sprocket wheels 98 before referred to. By means of this mechanism power can be transmitted from the motor 121 to drive the conveyer chains 89 in the direction indicated by the arrows in 30 Fig. 5.

The slack from the main under-cutter will be carried backward within the main frame 1, and will not be caught by the main conveyer. In order to pick up this slack and 35 load it with the other coal a supplementary slack conveyer is provided, this is clearly shown in Figs. 4, 6, 8, 9, 22, 23 and 24. The active element of the conveyer is a chain 140 which passes over a drive sprocket 141 mounted underneath the rear end of the main conveyer for rotation about a vertical axis. At the forward end the chain 140 passes around an idler sprocket 142 which is mounted in a bracket which is slidable longitudinally of the machine. Secured to the chain 140 are perpendicularly extending flights 143—143 which serve to engage the coal cuttings from the pan or sub-base near the point where they are dropped by the bits 45 of the cutter chain. The flights 143 push the cuttings onto an inclined trough 144, and finally discharge them into the same hopper casting 96 which receives the coal from the main conveyer. A similar trough 50 144^a is provided for supporting the return strand of the conveyer element.

The head sprocket 141 is journaled on a stud 145 which is integral with a casting 146 secured to the main frame 1 by means 55 of bolts 147, which also hold the plate 147^a

in place. A washer and cap screw 148 holds the sprocket in place. The front sprocket 142 is journaled on a stud 149 of the casting 150 and is held in place by means of a suitable guard 151. The casting 150 is supported for limited movement longitudinally of the machine by an extension 152 which engages a suitable guide way formed on the main casting 1. It is held against forward movement by the tension of the chain and 75 against rearward movement by the screw 154.

The rear parts of troughs 144 and 144^a are supported by means of angle bars 155—155. Other angle bars 156—156 are 80 arranged parallel to the bars 155—155 and coöperate with them to form guides for the chain 140. The bars 155—155 and 156—156 are secured at their rear ends to the parts 146 and 147^a and at their forward ends to 85 the castings 159 and 160. The casting 159 has near its forward end an upward projecting part 160'. Cross members 157 and 158 connect the rear parts of the opposite angle bars 155 and 156. The castings 159 90 and 160 are rigidly connected together and are also rigidly connected to the main frame by means of a foot 159' on the casting 159. The castings 159 and 160 have flanges 159^a—159^a and 160^a—160^a which align with 95 the angle bars 155 and 156 and serve as chain guides. At the lower end of the conveyer are angle bars 159^b—159^b and 160^b—160^b. Those on the left hand side as viewed in Fig. 24 are secured to the castings 150 100 and 151, and those on the right hand side are secured to the castings 159 and 160.

The adjusting screw 154 above referred to is supported in an aperture in the extension 160', and in apertures in the casting 159. It is held against rotation by means of a key 154^a, which is shown in Fig. 21. 161 is a nut mounted on the screw 154 in a recess formed in the casting 159. This nut 161 has formed upon it a bevel gear adapted 110 to mesh with a similar bevel gear 162. This gear 162 is mounted on a short transverse shaft 163 which is inclined upward and held in a bearing 163^a on the main frame. The shaft is squared at its end, and adapted to be engaged by a socket wrench to be turned. An operator by turning the shaft 163 can turn the nut 161 and thereby adjust the screw 154 and the sprocket 142 to change the 115 tension of the chain 140.

170 is the plate or pan upon which the main frame of the machine slidably rests. This pan 170 comprises a bottom plate 175, and side plates which are formed by angle bars 176 and 177. The inner edges of the 125 horizontal flanges of the angles 176 and 177 are positioned to engage the sides of the main frame casting 1, and to form a guide way for it. Attached to the vertical flanges of the angle bars 176 and 177 are supple- 130

mental guide strips 179 and 179^a, which are normally out of engagement with the main frame casting, but are adapted to contact with it in case the casting for any reason 5 jumps out of the main guide way.

The main frame is moved to advance the cutting and breaking down mechanisms into the coal by means of the rope controlled devices which will be described. These are 10 shown in Figs. 9 and 25. For feeding the machine forward a feed rope 173 is provided which is connected to be wound upon a drum 171 mounted on the main frame. From the drum 171 the rope extends over a 15 sheave 180 mounted on the main frame, and over a sheave 181 mounted at the forward end of the pan 170. A guide sheave 181^a is positioned adjacent the sheave 181. After 20 passing around the sheave 181 the rope extends backward to a sheave 182 mounted on the main frame and across to a similar mounted sheave 183. From the sheave 183 the rope extends forward to a point of attachment to the front end of the pan at 25 184. It will be clear that when the drum 171 is rotated the rope 173 will cause the main frame and attached parts to move forward with respect to the pan, the tractive force being divided between the two sides. 30 174 is a rope for pulling the main frame and attached parts backward with respect to the pan. This rope is connected to the winding drum 172, and from the drum extends backward between two guide sheaves 35 185—185. From the sheaves 185 the rope can extend to the right or the left and can be secured to one or the other of the hooks 185'—185', as shown in Fig. 25. It will be clear that when the drum 172 is 40 rotated the rope 174 will act directly to pull the main frame and attached parts backward.

The hooks 185'—185' are secured to or 45 formed as parts of castings 186—186 mounted at the rear corners of the pan 170. These castings 186—186 are provided with rearward extending lugs 187—187 adapted 50 to be engaged by lifting jacks or crow bars for handling the machine and assisting in 55 moving it about the mine. Mounted on the casting 186—186 are sheaves 186^a—186^a over which the rope 174 can be passed when it is to be used for moving the machine as a whole laterally or otherwise in a manner 60 to be hereinafter described.

The drums 171 and 172 are mounted for 65 rotation upon two stationary vertical shafts 190 and 191, the bottom ends of which are threaded into castings 192 and 193 suitably secured to the bottom wall of the main frame casting 1. The shafts have suitable extensions 194 and 195 which engage apertures in the bottom plate of the main casting to assist in preventing lateral displacement. The upper ends of the shafts

190 and 191 are fitted into apertures in a plate 196. Set screws 197—197 assist in holding the shafts against rotation.

Freely journaled upon the shaft 191 is a sleeve 197^a upon which is journaled the 70 drum 172, the drum being supported on a ball bearing 198 which rests upon the hub 199. This hub 199 is journaled on the shaft 191 and has secured to it an operating lever 200. The lower side of the hub 199 is 75 formed with beveled, or wedge shaped teeth, shaped to coöperate with similar teeth formed on the casting 193. The hub of the drum 172 is provided at 201 with an annular recess, and into this recess there extends 80 a cylindrical flange 202 which projects downward from a collar 203 formed on the sleeve 197^a. Mounted in the recess 201 is a series of clutch disks alternately keyed to the hub of the drum, and to the flange 202 85 in the usual manner. When the lever 200 is moved to turn the hub 199 in one direction, the teeth on the bottom of the hub co-act with the teeth on the casting 193 to lift the hub and the drum, thus pressing 90 the clutch disks together to cause the transmission of power from the sleeve 197^a to the drum. When the lever 200 is moved to turn the hub in the other direction the drum is lowered and the clutch is released. 95 Fitted to the upper part of the sleeve 197^a is a spur gear 204, and also a worm gear 205. 206 is a nut on the shaft 191 and between this nut and a shoulder on the shaft is a ball bearing 207 upon which rests a 100 ring 208 which is secured to the sleeve 197^a by the screw bolts which secure the gears 204 and 205. The ball bearing 207 thus serves to support the gears and the sleeve. Formed on the drum 172 is a cylindrical 105 flange 209, which forms an oil well in which the clutch is contained.

The drum 171 is mounted and driven similarly to the drum 172. 210 is a sleeve rotatably mounted on the shaft 190, and 110 upon this sleeve the drum 171 is journaled. The drum rests upon a ball bearing 211, which in turn rests upon a hub 212 carrying an operating lever 213. The hub 212 is formed with wedge shaped teeth similar to 115 those on the hub 199, and these teeth co-act with similar teeth on the casting 192. It is to be noted, however, that the teeth on the parts 212 and 192 are inclined oppositely from those on the parts 199 and 193 120 for a reason to be hereinafter explained. The hub of the drum 171 is provided with a recess at 214, and a flange 215 formed on the collar 216 of the sleeve 210 extends into this recess. In the recess are clutch disks 125 secured alternately to the hub and to the flange. The disks can be brought into or out of contact by turning the hub 212. Secured to the sleeve 210 is a spur gear 217 which meshes with the spur gear 204. A 130

ball bearing 218 is interposed between a nut 218^a and a shoulder on the shaft 190, and a ring 219 secured to the gear 217 and the sleeve 210 rests upon this ball bearing. In 5 this way the gear and the sleeve are supported. A cylindrical flange 220 extends upward from the drum and forms an oil reservoir for inclosing the clutch.

The rings 208 and 219 are provided with 10 oil recesses 221^a—221^b and from these recesses oil holes 221 extend downward to the clutches.

171^a and 172^a are guards partly surrounding the drums 171 and 172. They serve to 15 prevent the escape of loose coils of rope from the drums.

The operating levers 200 and 213 are connected together by means of a link 222. For holding the two levers in normal positions 20 so that both of the clutches are disengaged there is provided a spring balancing device which is connected to the hub 199 at 222^a. 222^b is a transversely slidable reach rod connected to the hub 199 at 222^a, and carrying 25 two arms 223 and 224 which are apertured to receive transverse bars 225 and 226, which are mounted between the parts 35 and 228 of the main frame casting 1. A spring 226^a is interposed between the arms 30 224 and the flange 35, and a similar spring 227 is interposed between the arm 223, and the rib 228. The two springs oppose each other and tend to hold the rod 222^b in central position and consequently to hold the 35 hubs 199 and 212 in central positions. Attached to the lever 200 is a chain 229 which passes over sheaves 230 and 231, and is wrapped around one end of a hollow transverse shaft 232, which is mounted in the 40 main frame, the end of the chain being secured to a collar 233 on the shaft. A chain 234 is secured to the lever 213 at 235 and bears against the segment 213^a, also secured to the hub 212. The chain 234 passes over 45 the sheave 236 and is wound upon the other end of the shaft 232, being secured to the collar 237. The chain 234 is wrapped in the opposite direction from the chain 229.

The hollow shaft 232 is supported at the 50 right hand end, looking toward the front of the machine, by means of the collar 233 which rests in a bearing aperture of the main frame. The other end of the shaft rests directly in a suitable aperture formed 55 in the other side of the main frame. Hand wheels 238—238 are keyed to the ends of the shaft, and by means of these hand wheels the shaft may be turned to actuate the chains.

60 To the hand wheel 238 on the left hand side of the machine is bolted a ratchet wheel 239 which is clearly shown in Figs. 25 and 30. This wheel is adapted to engage with either end of a double acting pawl 240, 65 which is pivoted to the main frame by means

of a stud 241. The pawl 240 has a tail 242 to which is secured a pin 243, which extends through the slot in a lever 244. This lever 244 is secured to a transverse shaft 245 which extends through and is journaled in 70 the hollow shaft 232. At the other end of the shaft 245 is a similar lever 246, which is shown in Fig. 4. Pivotally attached to the pin 243 is a rod 247 slidable in an aperture in the lug 248 on the lever 244. A 75 compression spring 249 abuts at its upper end against a nut on the rod 247, and at its lower end against the lug 248. The spring thus acts to press the rod and with it the pin 243, upward into the position shown in 80 Fig. 30. In this way the pawl 240 is rocked into engagement with the ratchet wheel 239. However, when the lever 244 is moved to its central vertical position the pawl will be disengaged from the ratchet wheel, and 85 the shaft 232 will be free to turn in either direction. By moving the lever 244 (or the lever 246) in one direction or the other the pawl can be brought into position to lock the ratchet wheel, and the shaft 232 against 90 rotation in either direction as desired.

When the operator desires to feed the machine forward to cause the cutting and breaking down mechanisms to advance into the coal he turns the shaft 232 by means of 95 one or the other of the hand wheels 238 in the direction to cause the chain 234 to be wound, thus engaging the clutch which controls the feed drum 171. As soon as the shaft has been turned sufficiently to engage 100 the clutch the lever 244 (or 246) is moved forward to the position opposite from that shown in Fig. 30, thus preventing the shaft from rotating in the direction to unwind the chain. When the operative parts have 105 moved forward to the extreme limit of their travel the levers 244 and 246 engage lugs 245^a—245^b on the bed or pan, the levers thus being moved sufficiently to release the pawl 240 and permit the clutch to be moved to 110 inoperative position by the spring mechanism 226^a and 227.

To retract the operative parts the operator then turns the hand wheel to rotate the shaft 232 in the other direction and cause 115 the engagement of the clutch for the pull back drum 172, it being assumed that the pull back rope 174 is connected to one of the hooks 185^a—185^b. As soon as the clutch is engaged, the lever 244 (or 246) is moved 120 to the rear position, as shown in Fig. 30 the pawl 240 then acting to prevent turning of the shaft, and thus to hold the clutch engaged. As soon as the parts reach the rear limit of travel the levers 244 and 246 engage 125 lugs 245^a—245^b on the pan, and are moved to their normal positions, thus disengaging the pawl from the ratchet wheel and permitting the clutch to be released by the spring mechanism at 226^a and 227.

- Power for operating the entire machine, except the rear, swinging conveyer, which is driven by the motor 121, is derived from the electric motor 250. This motor has a 5 pinion 251 on its armature shaft and the pinion meshes with a master bevel gear 252 which is keyed on a vertical shaft 253, shown in Fig. 8. This shaft is journaled in a bearing 254 of the main frame and carries at its 10 lower end the sprocket 10 for the under-cutting chain 8. The weight of the gear and of the shaft is carried by a ball bearing 255. Formed on the hub of the gear 252 is a smaller bevel gear 256 which meshes with a 15 similar bevel gear 257 on a transverse shaft 258. This shaft is mounted in bearings 259, 260 and 260^a formed in a plate 261 secured to the main frame. Loosely mounted on the 20 ends of the transverse shaft 258 are the sprocket wheels 29—29 for the shearing cutter chains 25—25. Keyed to the shaft 258 at points adjacent the sprocket wheels 29—29 are hubs 262 having flanges 263^a. These flanges are apertured at intervals and the 25 corresponding apertures are formed in the sprocket wheels. Clutch fingers 263—263 are mounted on plates 264—264 and these fingers can be moved through the apertures in the flanges 262^a, and into the apertures 30 in the sprocket wheels, thus serving to connect the sprocket wheels to the shaft. Latch bars 264^a—264^a are provided for holding the plates in or out of operative positions. These are mounted on pivot pins 265. 35 A spur gear 266 is mounted on a transverse shaft 267 and meshes with a pinion 268 on the shaft 258. The shaft 267 is mounted in a bearing 269 on the main frame. This construction is clearly shown in Figs. 6, 28 40 and 29. Keyed to the shaft 267 is a bevel gear 270 which meshes with a similar bevel gear 271 on a longitudinally extending sleeve 272. This sleeve 272 is freely mounted on a longitudinal shaft 273 which is supported in bearings 274 and 275. The sleeve 272 is connected with the shaft 273 by means 45 of the multiple disk friction clutch which comprises a driven member 276 secured to the shaft and disks 277 alternately secured to the sleeve and to the said driven member. The pressure between the disks can be adjusted by means of the nut 278 which is screwed on an extension of the driven member and which engages the disks by means 50 of the pins 278^a. Keyed to the shaft 273 is a hub 279 which forms the driving member of a second friction clutch. Journaled on the shaft 273 adjacent the hub 279 is a driven member 280 55 upon which is formed the drum 43, before referred to, for the pick mechanism controlling rope 38. Extending across the machine and journaled in suitable apertures 281^a in the side 60 parts of the main frame is a hollow shaft 281. To the ends of this hollow shaft are secured upward extending levers 282 for oscillating it. Mounted on the shaft 281 is an eccentric 283 which engages an eccentric rod 284. The rod 284 is connected at its 70 other end to a lever 285 which is pivotally mounted at 286 on a bracket 287 secured to the motor frame. The lever 285 is forked at its lower end to engage a ball bearing 288 on the shaft 273 between the lever and the 75 driven member 280. Friction clutch disks are interposed between the driving and driven members 279 and 280 and by grasping one of the levers 282 the operator can, by means of the mechanism which has been 80 described, move the member 280 longitudinally of the shaft, thus forcing the clutch disks firmly into contact and causing the drum 43 to be rotated. Formed on the levers 282—282 are casings 85 289—289 which contain the opening switches 71—71, before referred to. These switches are controlled by the buttons 75—75 within reach of the operator's thumb when his 90 hand is on the handle of the lever. Embracing the outer surface of the driven member 280 is a friction band 290, which is clearly shown in Fig. 19. The tension of this band can be adjusted by means of bolts 291—291. On the outer surface of the band 290 are formed ratchet teeth 291^a adapted 95 to be engaged by a pawl 292. The pawl 292 is mounted on a pivot pin 293, which is supported in lugs on the casting 293^a secured to the casing of the motor 250. A spring 292^a 100 tends to hold the pawl in operative position and a rod 294 is provided which extends entirely across the machine, and can be grasped at either end by the operator to release the pawl. 105 When it is desired to elevate the pick mechanism the operator grasps one of the levers 282 and moves it forward thus clutching the drum 43 to the shaft 273 and causing the rope 38 to be wound. This rope acts 110 through the pulley 37 and the arm 36 to elevate the mechanism. When the desired elevation is reached the pawl 292 engages the ratchet teeth on the friction band 290 and prevents the unwinding of the rope and the 115 consequent dropping of the mechanism. When it is desired to lower the pick mechanism the drum is rotated sufficiently by means of the clutch to release the stress on the pawl which can then be lifted by the 120 movement of the rod 294. The clutch is then partially released and the pick mechanism is allowed to lower by gravity under the control of the clutch. The friction connection between the band 290 and the drum 125 serves as a safety device to prevent any breakage of parts should the operator fail to properly control the mechanism by means of the clutch and the pawl. The crank pin 62 for the connecting rod 130

61 for driving the pick mechanism is mounted upon the gear 266 preferably being formed integrally therewith, as shown in Fig. 28. Upon this crank pin 62 is mounted 5 the disk 72 upon which is mounted the switch mechanism for energizing and de-energizing the electro-magnet.

Keyed to the shaft 273 near its rear end 10 is a worm 295 which engages with the worm wheel 205 for driving the rope drums 171 and 172. Also mounted on the shaft 273 is a bevel gear 296 which meshes with a bevel gear 297 attached to the sprocket wheel 141 of the slack conveyer. A second bevel gear 15 298 mounted on a transverse shaft 299 mounted on the main frame meshes with the gear 296. Upon one end of the shaft 299 is a sprocket wheel 300, and a chain 300^a passes over this sprocket wheel and over a similar 20 sprocket wheel 301 on the drive shaft 78 for the main conveyer.

302 is a flexible electric conductor leading to the terminal box 303 from which current is supplied to all parts of the machine. Preferably as shown diagrammatically in Fig. 31 25 a cable reel 302^a is provided for winding and unwinding the cable 302 as the machine moves. The electrical connections for the pick controlling mechanism, and for the 30 motor 121 for the swinging conveyer have already been described. 304 is a starting box of any usual or preferred type for controlling the motor 250. Journaled within the hollow shaft 281 is a second shaft 307. This 35 shaft 307 carries at the left hand end an arm 306 which is connected by means of a link 305 with the controlling lever of the starting box 304. Secured to the shaft 307 are operating levers 308—308 located at opposite 40 sides of the machine. By means of one or the other of these levers an operator on either side of the machine can start or stop the motor.

The pull back rope 174 is used to move 45 the machine bodily from place to place. When so used the rope is detached from the hook 185' and a sufficient amount is unwound to permit it to be attached to a jack or other stationary objects or to be passed 50 around pulleys on jacks such as those indicated at 317 and 318. In order to avoid the delay which would be occasioned by the rewinding of the cable to permit adjustment to one of the hooks 185'—185' I prefer to 55 provide clamps such as are shown in Figs. 26 and 27. These clamps are indicated by 309, each consists of two grooved plates which can be forced together to grip the rope by means of a nut 311 on a screw 310. A removable bar 312 is provided for turning the nut. When the clamp is in use, the rope 174 can be used for pulling the machine backward 60 on the pan, a large part of the rope at the same time being left free to be at-

tached to a jack or passed around guide pulleys when desired.

At 313, as shown in Figs. 2 and 7 holes are provided for the attachment of hooks such as that indicated by 314. By means of such a hook the rope 174 can be attached to the front end of the machine or to other parts.

In operating the machine it is first placed in position near one rib, preferably the left, of a room as indicated in Fig. 32. Preferably the forward end of the machine is inclined outward away from the room axis. The pan 170 is jacked in place to prevent movement, a jack for this purpose being diagrammatically indicated in Figs. 32 to 36. The main motor 250 is then started and by means of the power transmitting devices which have been described the under-cutting and shearing cutter chains are started, the main and slack conveyers are started, and the driving pistons for the pick mechanism are started. A pit car 314 is suitably placed on a track in the center of the room, and the swinging conveyer is laterally adjusted to bring the discharge end over the car. The swinging conveyer is started by means of the snap switch 123.

The operator by turning one of the hand wheels 238 throws in the clutch which drives the drum 171 for the feed rope 173, and the whole mechanism is caused to advance bodily with respect to the pan 170, the cutters 9—9 forming a horizontal kerf and the cutters 28—28 forming parallel vertical kerfs. At the same time the front end of the main conveyer is carried into the kerf formed by the cutters 9—9.

As the machine advances the pick mechanism is started and slowly raised, the operator controlling the mechanism by means of one of the levers 282 in the manner before described. He can not only regulate the speed at which the mechanism is lifted, but he can also by pressing the button 75 hold the picks temporarily idle. The coal broken down by the pick mechanism falls onto the main conveyer and is carried backward by it and dumped into the hopper 97 and onto the swinging conveyer which carries it upward and backward into the car 314. The cutting and conveying mechanism is entirely automatic after once being started, and the operator can devote his entire attention to controlling and regulating the operation of the breaking down mechanism. It is obvious that the breaking down of the coal requires considerable care not only to prevent too rapid breaking to choke the conveyer, but also to prevent too slow breaking which would permit the cutters to get too far ahead of the picks. It will be noted, as before pointed out, that I have shown in the drawings shear cutters adapted to cut kerfs

which terminate behind the front vertical plane of the horizontal kerf. Because of the vertical forward edges of the vertical kerfs, the coal between the kerfs has very little natural support and is very easily broken. In fact under some conditions it is broken so easily that it would fall too rapidly under the action of the pick mechanism, were it not for the fact that the vertical kerfs 5 terminate several inches behind the horizontal kerfs, thus giving a better support for the coal and preventing the rapid breaking. It will be understood that as to this point there can be variations in accordance with 10 the conditions. The cutting, breaking down, and carrying away of the coal continues in the manner described until the mechanism reaches the extreme limit of its forward movement, when the feeding mechanism is 15 automatically disconnected by the engagement of the lugs 245'-245' with the levers 244 and 246 in the manner before described. The operator then throws the hand wheel 238 in the other direction and connects the 20 drum for winding the pull back rope 174. The mechanism is then retracted until the drum is automatically disconnected by the engagement of the lugs 245^a-245^a with the levers 244 and 246. The machine is then 25 ready to be moved to a new position. To accomplish this the rope 174 is arranged, as shown in Figs. 32, 33 and 34, it being passed over pulleys secured to jacks 317 and 318 and secured at its outer end to the forward 30 end of the pan 170. The drum 172 is then set in motion and the rope is wound, the result being that the machine is pulled laterally into the position shown in Fig. 34. It is then ready to be jacked in position and 35 40 again operated in the manner before described. This series of operations can be repeated until the machine reaches the position shown in Figs. 35 and 36 in which it is inclined oppositely from the position shown in Fig. 32. This outward inclining of the machine serves to keep the width of the room substantially constant as the machine advances.

When the last cut is finished the jack 116 45 is removed and a jack 118 is set near the face of the coal and the free side of the machine. The rope 174 is then transferred to the other side of the machine and carried forward over a snatch block 319 attached 50 to the forward corner of the pan. The drum 172 is then set in motion and the whole machine is moved bodily forward into position for another cut. The cuts of the next series are taken from right to left instead of from 55 left to right. As soon as this series of cuts is completed the machine will be back in a position such as indicated in Fig. 32, and the whole cycle of operation can be repeated.

It will be understood that use may be

made in handling the machine of jacks, 65 skids, rails, etc., such as may be necessary to meet local conditions. The use of such devices is well understood by mine engineers, and mine operators, and a detailed description is unnecessary. 70

It will be understood that suitable guards may be provided for the various operative parts of the machine to protect the operators. Guards for the shear cutting mechanism are indicated at 321-321. Other 75 guard devices have been omitted from the drawings for the sake of clearness.

Attention is especially called to the fact that all of the controlling devices for the machine are provided in duplicate, one set 80 being mounted on each side. Because of this it is possible for the machine to be brought close to either rib and for it to be controlled from the side opposite to the rib.

It will be observed that the electro-magnet 85 for the pick mechanism is capable of being controlled in a manner different from that before described. One or both of the switches 71-71 can be locked in open position and the rheostat or variable resistance 90 at 68 can be so adjusted as to make the strength of the magnet such that it will automatically release the armature 66 when the springs 51-51 approach maximum compression. The pick mechanism can be held 95 inoperative by adjusting the rheostat to cut out some of the resistance, and thus increase the strength of the magnet. This method of control is preferable under conditions in which explosive gases are likely to be met 100 with, as it eliminates the possibility of sparks which might occur if the switch 72 were used.

I am aware that numerous proposals have been made for machines intended for cutting, breaking down and loading coal, but my improved machine differs from earlier proposals in certain important respects, and especially the following: It has been proposed to provide a machine having a horizontal kerf cutting apparatus and lateral shearing cutters with a plate arranged to receive the separated coal and a conveying mechanism comprising a shovel which alternately advances and recedes in relation to 105 the receiving plate, delivering its coal when it recedes upon an endless conveyer. I have found from experience that it is essential to provide a continuously moving conveyer disposed between the lateral shear cutters 110 in position to enter the horizontal kerf and extend to points near the front of the horizontal kerf cutting apparatus, and adapted to be there maintained during the cutting operation in position to receive the coal dislodged from the over-lying bulk between the shear cutters. It has also been proposed to provide a mining and loading ma- 115 120 125

chine with a conveyer arranged to enter the horizontal kerf in the coal, but no provision was made in connection with such proposal for the formation of lateral vertical kerfs and it has been found impossible to successfully operate such machines because of the impossibility of suitably breaking down the coal by means of pick devices unaided by lateral shear cutters.

10 The particular form of shear cutters which I employ is important in connection with the general method of operation for which the machine is intended. That is to say, the machine is designed to work along 15 the face of the coal making successive cuts by the reciprocation of the carriage on the bed frame, the machine as an entirety being moved laterally after each cut into position for the succeeding cut. To successfully 20 carry out such a plan of operation, it is practically necessary that the coal removed on each individual cut should be separated in such a manner as to leave a straight vertical face, and also that there shall be effective 25 provision for the lateral movement of the machine in its entirety. To this end I have provided vertical shear cutters of the endless chain type having their front sides terminating in vertical lines near the front 30 sides of the horizontal kerf cutting mechanism and the conveyer which coöperates therewith; and this form of cutting apparatus supplemented by the breaking means insures the breaking down of the coal so as 35 to leave a substantially straight vertical face at the completion of each cut. And when the cut is completed and the carriage retracted, the apparatus as a whole is readily moved laterally over the mine floor by 40 the power devices which I provide, use being made preferably of the carriage retracting cable for this purpose.

The construction and arrangement of the kerf cutting mechanisms of my machine in 45 relation to the endless conveyer and to the driving mechanism are of considerable importance. It will be observed that the frames of both the horizontal and the vertical cutting mechanisms are extended well 50 backward to points adjacent the space beneath the upper part of the conveyer, and in this space is disposed, to great advantage, the driving mechanism which can readily be connected to the adjacent drive 55 sprockets of the kerf cutting mechanism. This relative arrangement of the parts of the machine I have found to be of great practical advantage.

Another important feature of my machine 60 has to do with the secondary, swinging conveyer. By pivotally mounting this conveyer on the machine it is adapted to swing laterally in relation to the carriage and bed frame of the machine when the latter are 65 moved laterally along the face of the coal;

and thus it is possible to keep the delivery end of the swinging conveyer at a fixed point of discharge, for example over the cars on a track in the center of the room. Furthermore, I have provided driving 70 means for the swinging conveyer which is controllable independently of the main conveyer and thus it is possible to temporarily stop the swinging conveyer while cars are shifted without stopping the operation of 75 the other parts of the machine.

One of the difficulties encountered in connection with prior machines relates to the mechanism for feeding the cutters and for swinging and supporting the coal breaking 80 mechanism. The reciprocatory, percussive action of the breaker mechanism subjects the machine to incessant shock and vibration and, as prior machines of this class have employed feeding and controlling 85 mechanism comprising gear wheels, rapid deterioration of said mechanism by crystallization has resulted from the shock and vibration referred to. In my machine that part of the carriage feeding and breaker 90 swinging mechanism which receives the first shock incident to the vibration of the breaker is in the form of flexible cables, which, of course, are tension members and can be made of relatively soft metal that 95 does not readily crystallize.

The form and arrangement of the pick mechanism in my machine has a peculiar advantage. It will be observed that the coal engaging tools are mounted on the cross bar 100 by a substantially U-shaped frame which is itself slidably mounted upon a similarly shaped guide frame. This latter frame spans the longitudinally extending conveyer and has the rear ends of its side arms pivotally mounted on the main carriage frame at opposite sides of the rear elevated part of the conveyer. With this construction it is possible to thus pivotally support the breaker frame at comparatively low points 110 in relation to the conveyer and yet the front tool carrying cross bar can be swung well downward without interfering with the movement of coal on the conveyer.

What I claim as my invention is:

1. In a machine for cutting, breaking down and loading coal, the combination of a bed frame, a carriage movable forward and backward on the bed frame, a horizontal kerf cutting mechanism mounted on the carriage, two vertical shear cutting mechanisms mounted on the carriage and arranged to cut vertical kerfs disposed adjacent the sides of the horizontal kerf and terminating at their inner ends in vertical 125 lines, an endless carrier on the carriage arranged to extend into the horizontal kerf and adapted to continuously move to and from points near the front sides of the horizontal kerf cutting mechanism, means for 130

breaking the coal directly down upon the conveyer, said means comprising adjustably mounted reciprocating pick devices adapted to attack the coal between the vertical cutters at a transverse vertical plane near the inner ends of said vertical cutters, means for advancing and retracting the carriage on the bed frame, and means for moving the machine laterally when the carriage is retracted.

2. In a machine for cutting, breaking down and loading coal, the combination of a bed frame, a carriage movable forward and backward on the bed frame, a horizontal kerf cutting mechanism mounted on the carriage, an endless conveyer extending to points near the front of the horizontal kerf cutting mechanism and adapted to enter the kerf formed thereby, two shear cutting mechanisms mounted on the carriage and arranged to form vertical kerfs adjacent the sides of the horizontal kerf and terminating at their inner ends in vertical lines, means for feeding the carriage forward to force the kerf cutting mechanisms into the coal, said means comprising adjustably mounted reciprocating pick devices adapted to attack the coal between the vertical cutters at a transverse vertical plane near the inner ends of said vertical cutters, means for retracting the carriage and means for moving the entire machine laterally when the carriage is retracted.

3. In a machine for cutting, breaking down and loading coal, the combination of a bed frame, a carriage mounted to move forward and backward on the bed frame, horizontal kerf cutting mechanism mounted on the bed frame, mechanism for cutting vertical kerfs at the sides of the horizontal kerf comprising vertical plates having vertical front edges and cutter chains traveling in vertical planes around said plates to form kerfs terminating in lines in transverse vertical planes near the front side of the horizontal kerf cutting mechanism, a conveyer arranged between the planes of the vertical kerf cutting mechanisms to extend into the horizontal kerf and moving on lines parallel to the vertical kerf cutting mechanisms, means for breaking the coal and causing it to fall directly upon the conveyer, said means comprising adjustably mounted reciprocating pick devices adapted to attack the coal between the vertical cutters at a transverse vertical plane near the inner ends of said vertical cutters, power actuated devices for reciprocating the carriage to move the horizontal and vertical kerf cutting mechanisms and the breaking means into and out from the coal, and means for moving the entire machine laterally after the parts have been withdrawn from the coal.

4. In a machine for cutting, breaking

down and loading coal, the combination of a frame movable forward and backward, a horizontal kerf cutting mechanism mounted on said frame and having an elongated frame, an endless cutter chain traveling around said frame and a drive sprocket for the cutter chain mounted at the rear end of said frame, an endless conveyer extending downward and forward over the horizontal cutter frame to points near the front side thereof, vertical kerf cutting mechanism mounted on the said frame to cut kerfs at the sides of the horizontal kerf, each of said mechanisms comprising an elongated vertical frame extending from points near the front of the horizontal kerf cutting mechanism to points laterally opposite the rear part of the horizontal kerf cutting frame, an endless cutter chain on said vertical frame, and a drive sprocket for said cutter chain mounted at the rear end of the vertical frame, driving mechanism disposed under the rear elevated part of the endless conveyer and operatively connected to the three driving sprockets of the horizontal and vertical kerf cutter chains, and coal breaking means disposed directly above the conveyer.

5. In a machine of the class described, the combination with a kerf cutter comprising a horizontally disposed cutter frame and a cutter chain carried by said cutter frame adapted to form a horizontal kerf in the base of a coal vein and to discharge its cuttings rearwardly of said cutter frame, of dislodging mechanism adapted to dislodge the material above the kerf cutter, a system of conveyers adapted to receive and remove said material as it is dislodged, and means to recover said cuttings and deliver them to the conveyer system.

6. In a machine of the class described, the combination with a kerf cutter comprising a horizontally disposed cutter frame and a cutter chain carried by said cutter frame adapted to form a horizontal kerf in the base of a coal vein and to discharge its cuttings rearwardly of said cutter frame, of dislodging mechanism adapted to dislodge the material above the kerf cutter, a system of conveyers adapted to receive and remove said material as it is dislodged, and means comprising an auxiliary conveyer adapted to recover said cuttings and deliver them to said conveyer system.

7. In a machine for cutting, breaking down and loading coal, the combination of a bed frame, a carriage movable forward and backward on the bed frame, an undercutting mechanism mounted on the carriage and adapted when the carriage is moved forward to cut a horizontal kerf in a coal face, a breaking down device mounted on the carriage above the undercutting mechanism, a conveyer mounted on the carriage with its forward end underneath the break-

ing down device in position to enter the kerf formed by the undercutting mechanism, and a supplemental conveyer underneath the first said conveyer for receiving slack carried backward by the undercutting mechanism to points underneath the first conveyer, said conveyers having a common point of delivery.

8. In a machine for cutting, breaking down and loading coal, the combination of 10 a bed frame, a carriage movable forward and backward on the bed frame, an undercutting mechanism mounted on the carriage and adapted when the carriage is moved 15 forward to cut a horizontal kerf in a coal face, a breaking down device mounted on the carriage above the undercutting mechanism, a conveyer mounted on the carriage with its forward end underneath the breaking 20 down device and positioned to enter the kerf cut by the undercutting mechanism, a supplemental conveyer underneath the first said conveyer for receiving slack carried backward by the undercutting mechanism to 25 points underneath the first conveyer, and a third conveyer positioned to receive material discharged from both of the aforesaid conveyers.

9. In a machine of the class described, the 30 combination with a bed frame, of a carriage movable forward and backward on the bed frame, cutting devices mounted on the carriage comprising a horizontally disposed cutter frame and a cutter chain carried by 35 the cutter frame adapted to form a horizontal kerf at the base of the coal vein when the carriage is moved forward, breaking down devices adapted to dislodge the material above the horizontal kerf, loading devices 40 comprising a conveyer mounted on the carriage in position to receive the dislodged material, a driving sprocket wheel engaging the cutter chain and mounted on a carriage at one side of the central longitudinal vertical plane of the carriage, and an auxiliary 45 conveyer mounted on the other side of said vertical longitudinal plane adapted to receive the slack carried backward by said cutter chain and deliver it to the above mentioned loading devices.

10. In a machine of the class described, the combination of a bed frame consisting of a sheet metal pan resting directly upon the mine floor, a carriage comprising a main 55 frame resting directly upon the pan and slideable backward and forward thereon, cutting, breaking down and loading devices carried by said carriage, said cutting devices including a horizontally disposed cutter frame and a cutter chain carried by said cutter frame adapted to form a horizontal kerf in the base of the coal vein when the carriage is moved forward and to deliver its cuttings rearwardly in the pan, a conveyer consisting 60 of two rearwardly and upwardly inclined

parallel chutes and a chain mounted to travel along said chute and having conveyer elements adapted to engage the material on the pan and carry it up one of said chutes and deliver it to the above mentioned loading 70 devices.

11. In a machine of the class described, the combination with a bed frame, of a carriage movable forward and backward on the bed frame, feeding mechanism comprising 75 two independently rotatable drums mounted on the carriage, a rope connected with the forward end of the bed frame and adapted to be wound upon one of the drums to move the carriage forward, a second rope 80 adapted to be wound upon the other drum, means to connect the second rope to the rear end of the bed frame whereby the carriage may be moved backward, and means usable alternately with said connecting means for 85 guiding said second rope laterally whereby the machine may be moved bodily relative to the coal face.

12. In a machine of the class described, the combination of a bed frame, a carriage 90 movable forward and backward on the bed frame, feeding devices comprising two independently rotatable drums mounted on the carriage, a rope connected with the forward end of the bed frame and adapted to be 95 wound upon one of the drums to move the carriage forward, a second rope adapted to be wound upon the other drum, means to connect said second rope to the rear end of the bed frame whereby the carriage may be 100 moved backward, and means usable alternately with said connecting means for guiding said second rope laterally in either direction whereby the machine may be moved bodily in either direction relative 105 to the coal face.

13. In a machine of the class described, the combination with a bed frame, of a carriage movable forward and backward on the bed frame, feeding mechanism comprising 110 two independently rotatable drums mounted on the carriage, a rope connected to the forward end of the bed frame and adapted to be wound upon one of the drums to move the carriage forward, a second rope 115 adapted to be wound upon the other drum, means to connect the second rope to the rear end of the bed frame whereby the carriage may be moved backward, means usable alternately with said connecting means for 120 guiding the second rope laterally in either direction, and means for connecting the end of said rope to the forward end of the bed frame at either side thereof whereby the rope when passed over pulleys external of 125 the machine may be used to apply lateral draft simultaneously to both ends of the machine to move it bodily relative to the coal face.

14. In a machine of the class described, 130

the combination with a bed frame, of a carriage movable forward and backward on the bed frame, feeding mechanism mounted on the carriage comprising a rotatable drum, 5 a rope adapted to be wound upon the drum, guide sheaves mounted at the side of the bed frame at the rear end thereof adapted to guide said rope laterally, and gripping devices upon the bed frame adapted to en- 10 gage said rope whereby the carriage may be moved backward.

15. In a machine of the class described, the combination with a bed frame, a carriage movable forward and backward on the bed frame, feeding mechanism comprising two independently rotatable drums mounted upon the carriage, a rope connectible to the bed frame and adapted to be wound upon one of the drums to move the carriage in 20 one direction, a second rope connectible to the bed frame and adapted to be wound upon the other drum to move the carriage in the other direction, and means usable alternately with one of said rope connecting 25 means for guiding its rope laterally whereby said rope may be used to move the machine bodily relative to the coal face.

16. In a machine for cutting, breaking down and loading coal, the combination of 30 a bed frame, a carriage movable forward and backward on the bed frame, an under-cutting mechanism mounted on the carriage and adapted when the carriage is moved forward to cut a horizontal kerf in the coal face, the said mechanism comprising a horizontal frame and an endless cutter chain mounted to travel around the periphery of the frame, a breaking down device mounted on the carriage above the under-cutting 35 mechanism, a conveyor mounted on the carriage with its forward end beneath the breaking down device, two shear cutting mechanisms mounted on the carriage and positioned to cut two vertical kerfs adjacent 40 the sides of the horizontal kerf when the carriage is moved forward, each of the said mechanisms comprising a vertical frame plate and an endless cutter chain mounted to travel around the periphery of the plate, 45 and two longitudinally extending guards, each positioned to close the space between one side of the frame for the under-cutting mechanism and the frame plate for the corresponding shear cutting mechanism.

55. 17. In a mining machine, the combination of a bed frame, a carriage movable forward and backward on the bed frame, cutting mechanism mounted on the carriage, power means for driving the cutting mechanism, 60 two independently operable power means adapted respectively to feed the carriage forward and retract it, each of said last named power means comprising a driving clutch, automatically acting means tending

normally to maintain both of said clutches 65 open, manually controllable means for holding said clutches closed against the action of said automatic means, and means for automatically rendering the said manual means inoperative when the carriage approaches 70 the ends of its travel on the bed frame.

18. In a machine for cutting, breaking down and loading coal, the combination of a frame adapted to move forward and backward, horizontal kerf cutting mechanism 75 mounted on said frame, a conveyer extending longitudinally of said frame forward and downward to points near the front side of the horizontal kerf cutting mechanism in position to enter the kerf formed thereby, 80 and breaking means adapted to break the coal down upon the conveyer, said breaking means comprising elongated vertically swinging guides having their rear ends pivotally mounted on the first mentioned frame 85 at opposite sides of the conveyer and adjacent the rear elevated part thereof, a U-shaped frame slidably mounted on said guides with its cross member disposed directly over the forward lower part of the 90 conveyer, coal engaging tools mounted in said cross member, and means for reciprocating the U-shaped carrying frame.

19. In a machine for cutting, breaking down and loading coal, the combination of 95 a frame adapted to move forward and backward, an under-cutting mechanism mounted on the frame, a longitudinally extending conveyer mounted on the frame and extending forward and downward to points adjacent the under-cutting mechanism, and a breaking down mechanism mounted on the frame above the conveyer and comprising two parallel hollow legs pivotally connected at their rear ends to the said frame, one 100 at each side of the conveyer, two tubes telescopically mounted respectively in the legs, a cross piece connecting the forward ends of the tubes, a series of picks mounted on the cross piece and means for reciprocating the 110 tubes.

20. In a machine for cutting, breaking down and loading coal, the combination of a frame adapted to move forward and backward, an under-cutting mechanism mounted 115 on the frame, a longitudinally extending conveyer mounted on the frame and extending downward and forward to points adjacent the under-cutting mechanism, and a breaking down mechanism mounted on the frame above the conveyer and comprising two parallel hollow legs pivotally connected at their rear ends to the said frame, one at each side of the conveyer, a cross piece connecting the legs at their forward ends, two tubes telescopically mounted respectively in the legs, a cross piece connecting the forward ends of the tubes, a series of picks mounted on 120

125

the cross piece and means for reciprocating the tubes.

21. In a machine for cutting, breaking down and loading coal, the combination of a frame adapted to move forward and backward, an under-cutting mechanism mounted on the frame, a longitudinally extending conveyer mounted on the frame and extending downward and forward to points adjacent the under-cutting mechanism, and a breaking down mechanism mounted on the frame above the conveyer and comprising two parallel guides pivotally connected at their rear ends to the said frame, one at each side of the conveyer, a cross piece mounted on the guides to reciprocate longitudinally with respect thereto, a series of picks mounted on the cross piece, reciprocable cross heads mounted respectively in the guides and connected with the cross piece, two rocker arms mounted respectively adjacent the rear ends of the guides, connecting rods between the cross heads and the respective

arms, and means for simultaneously oscillating the arms. 25

22. In a machine of the class described, the combination of a bed frame, a carriage movable forward and backward on the bed frame, feeding mechanism comprising two independently rotatable drums mounted on the carriage, ropes windable on the drums adapted respectively to feed the carriage forward and backward, means to actuate each drum comprising a driving clutch, automatically acting means tending normally to maintain both of said clutches open, and manually controllable means for holding said clutches closed against the action of said automatic means. 30 35

In testimony whereof I affix my signature 40 in presence of two witnesses.
